UNITED STATES PATENT OFFICE.

HYMAN COHEN, OF BROOKLYN, NEW YORK.

TROUSERS-WAISTBAND.

1,166,113.

Specification of Letters Patent. Patented Dec. 28, 1915.

Application filed August 4, 1915. Serial No. 43,564.

To all whom it may concern:

Be it known that I, HYMAN COHEN, a citizen of the United States, residing at 1359 East New York avenue, in Brooklyn, 5 Kings county, State of New York, have invented certain new and useful Improvements in Trouser-Waistbands, fully described and represented in the following specification and the accompanying drawings, forming a part of the same.

The object of this invention is to furnish a means of forming a waistband upon a trousers, without exposing any of the seams to view, except the usual one which defines 15 the lower edge of the waistband upon the outer side of the garment. This object is attained by providing the stiffener of the waistband with a wide binding at one edge, of the same material as the waistband, and 20 basting this stiffener to the top of the trousers, with its edge under a narrow fold of the trousers cloth; and placing one edge of the waistband lining upon such binding, and stitching the whole together by a line of 25 stitches extended through the body of the trousers, and then bending such lining upward over the stiffener, and overhanding its upper edge to the top of the trousers. By this construction, the upward folding of the 30 lining wholly conceals the stitches which connect the lining to the waistband, and the lining is stretched tightly between the stitching at its opposite edges, so as to be held smoothly and firmly, and incapable of 35 wrinkling when the trousers are in use.

The invention will be understood by reference to the annexed drawing, in which—

Figure 1 is a perspective view of a trousers flap carrying part of the waistband; 40 only the stiffener and its binding being shown in place; Fig. 2 is an end view of the stiffener and its binding; Fig. 3 is a section of the stiffener; Fig. 4 is a section of the binding for the stiffener; Fig. 5 is a section 45 of the flap parallel with the edge of the fly b; Fig. 6 is an elevation of the flap with the waistband completed; Fig. 7 is a section like Fig. 5 with the lining attached in its reversed position; and Fig. 8 is a similar 50 view with the waistband completed.

In Figs. 1 and 6 a flap a of the trousers is shown, with a fly b attached, to carry the button-holes c. A fold d is made at the top edge of the trousers to which the upper edge 55 of the stiffener e is fitted, after the wide

binding f is secured thereto by stitches g, which do not therefore penetrate the cloth of the flap a. (See Fig. 1.) The lining i of the waistband is then applied to the binding f in a reversed position, as shown in Fig. 7, and a line of stitching h is extended through the edge of the lining, the binding, the stiffener, and the cloth of the trousers. This stitching is usual upon the outer side 60 of the waistband, and is the only stitching 65 that thus shows. The lining is then turned upward, as shown in Fig. 8, its upper edge folded inward flush with the top of the trousers, and is overhanded thereto, as indicated by the stitches k in Figs. 6 and 8. When 70 turned upward, the fabric of the lining is drawn tightly toward the top of the trousers, so that the sewing thereto holds it smooth, and wholly prevents any displacement or wrinkling when the garment is 75 worn.

The parts required in the construction of the waistband are few in number, consisting of the stiffener, the binding f, and the lining strip i, and all the work is done upon a 80 sewing-machine excepting the final overhanding, which avoids the exposure of any stitches upon the outer side of the waistband.

I am aware that it is common to conceal 85 stitching by various methods, but claim the particular means by which I form the waistband with a smooth, tight lining, and avoid any extension of the stitching to the outer side of the trousers, excepting the usual line 90 of stitches h.

The object of the binding f, secured independently upon the lower edge of the stiffener, is to inclose such edge, which would otherwise show when the lining was secured thereto; and the attachment of the lining to 95 the stiffener first in a reversed position enables the lining strip to serve as a cover for the stitches h, when the lining is turned upwardly to cover the entire stiffener.

The stiffener e and its binding f are shown 100 in Fig. 1 extended under the cloth of the fly b, as is common, and the end of the finished waistband is in like manner extended under the fly, but this is immaterial to my invention, which relates only to the formation of 105 the band itself.

What I claim and desire to secure by Letters Patent, is:—

A waistband for trousers, consisting of a stiffener having its upper edge inclosed in 110

a fold at the top of the trousers, an independent binding folded over the inner and outer sides of the stiffener at its lower edge, a lining having its bottom edge stitched to the cloth of the trousers through the edges of such binding and the body of the stiffener, and the lining extended over the

face of the stiffener and its top folded inwardly and overhanded to the fold at the top of the trousers.

In testimony whereof I have hereunto set my hand.

10

HYMAN COHEN.
